(57) CLAIM

The ornamental design for a dual-sole shoe with outpatch sole, as shown and described.

DESCRIPTION

FIG. 1 is a perspective view of an embodiment of our new design of a dual-sole shoe with outpatch sole;

FIG. 2 is a first side view of the design of FIG. 1;

FIG. 3 is a second side view of the design of FIG. 1;

FIG. 4 is a top view of the design of FIG. 1;

FIG. 5 is a bottom view of the design of FIG. 1;

FIG. 6 is a front view of the design of FIG. 1; and,

FIG. 7 is a back view of the design of FIG. 1.

The broken lines immediately adjacent to the claimed surfaces represent boundaries of the claimed design. The broken lines and the surfaces bounded by the broken lines form no part of the claimed design.
